UNITED STATES PATENT OFFICE.

OSWALD H. HANSEN, OF MILWAUKEE, WISCONSIN, ASSIGNOR OF ONE-HALF TO THE WISCONSIN CHAIR COMPANY, OF PORT WASHINGTON, WISCONSIN.

CAN-FILLING MACHINE.

1,359,367.

Specification of Letters Patent. Patented Nov. 16, 1920.

Application filed March 26, 1917. Serial No. 157,308.

To all whom it may concern:

Be it known that I, OSWALD H. HANSEN, a citizen of the United States, residing at Milwaukee, in the county of Milwaukee and 5 State of Wisconsin, have invented a certain new and useful Improvement in Can-Filling Machines, of which the following is a specification.

This invention relates to improvements in 10 the construction of machines for feeding fluent substances to receptacles, and particularly to improvements in machines for filling cans, jars, bottles or the like with liquids or other fluent substances such as 15 peas, beans, corn, tomatoes, berries or the like.

An object of the invention is to provide 20 a machine for feeding fluent substances to receptacles, which is simple in construction and efficient in operation. Another object is to provide means for reducing to a minimum 25 the manufacturing cost of filling machines. A further object is to provide means whereby a filling machine of one type may 30 be readily converted into a filler of another type, without necessitating replacement of the entire machine.

A number of types of machines adapted 35 to automatically fill or partially fill receptacles with fluent substances, have been on the market for many years. It has been customary in the manufacture of these machines of the prior art to arbitrarily construct each individual type of machine, 40 without regard to the structural details of other types. The result of such arbitrary construction is that manufacturers exploiting several types of these prior fillers are required to develop independent sets of patterns, 45 jigs and other special machinery for the manufacture of each type of filler, and the manufacturing cost of machines for which there is little demand is consequently excessively high.

It has been found that there are numerous details of construction in many of these filling machines, which may be made common to all of them, thereby necessitating but a single set of patterns, jigs and other 50 machinery in order to construct various types of fillers. By standardizing these common structural details and utilizing them in the construction of all types of fillers, the manufacturing cost may be reduced to a minimum and the selling price of 55

machines for which there is little demand, may be considerably reduced.

With the present invention, various types of filling machines are provided with common can feeding means, driving mechanism 60 and frame members which elements are constructed to coöperate with any of a number of types of measuring and feeding mechanisms. The measuring and feeding mechanisms are constructed for interchangeable insertion in the standardized frame, thereby permitting ready transformation of 65 a filling machine from one type into another.

A clear conception of an embodiment of 70 the invention may be had by referring to the drawings accompanying and forming a part of this specification, in which like reference characters designate the same or similar parts in the various views.

Figure 1 is a transverse vertical section through a filling machine embodying a corn measuring and feeding mechanism.

Fig. 2 is a fragmentary transverse vertical section through a filling machine embodying a pea measuring and feeding mechanism.

Fig. 3 is a fragmentary transverse vertical section through a filling machine embodying a syrup or brine measuring and 85 feeding mechanism.

Fig. 4 is a transverse horizontal section through a filling machine, the section being taken along the line IV—IV of Fig. 3 looking in the direction of the arrows.

The various elements which are common to all types of receptacle filling machines to which the present invention is applicable, will be first described. These common elements may with the aid of the present invention be standardized by the manufacturer, thereby eliminating necessity of duplicating parts.

The common frame comprises a pair of spaced upright elements 2 connected at their lower extremities by means of parallel bars 12 and at their upper ends by means of the element 7 having a centrally disposed hub 29 formed integrally therewith. The hub 29 is provided with a screw threaded 100 through opening. Pads 11 formed on the elements 2 are connected by and form supports for the gear casing 9 which also has a centrally disposed hub formed integrally 105 therewith. Other pads 10 located upon the

- frame elements 2 above the pads 11, are connected by and form supports for the can supporting and guiding frame 3. Pads 8 located upon the frame elements 2 above the pads, 10, serve in some instances as supports for cam tracks and in others to support structure forming part of the measuring and feeding devices, as will be later explained.
- 5 The common driving mechanism comprises a power shaft 6 supported in bearings formed integral with the gear casing 9 and having gears 5, 37 secured thereto, see Figs. 1 and 4. The shaft 6 is rotatable by means of power applied to a pulley 42, the driving connection between this pulley and the shaft 6 being manually controllable by means of a clutch 41. The bevel gear 5 meshes with a larger bevel gear 4 secured 10 to the lower extremity of the vertical shaft 1. The vertical shaft 1 is rotatably supported in bearings in the gear casing 9 and in a sleeve which is vertically adjustably supported in the hub 29 of the frame element 7. The gear 37 meshes with a gear 39 carried by the lower extremity of the vertical shaft 38. The shaft 38 is mounted in a bearing secured to the gear casing 9. The upper end of the shaft 38 is provided with 15 a rotary horizontally disposed can discharging disk 40, a portion of which projects over one side of the can supporting and guiding frame 3. A can remover 43 located above the disk 40 and extending into the path of the cans 13 serves to insure proper removal of the filled cans.
- 20 The common can transporting means which also includes the can discharging means previously described, comprises a can feeding and guiding frame 44 which terminates above the frame 3, and a can conveying element 14 secured to the vertical shaft 1. The element 14 is provided with peripheral recesses adapted to successively engage the cans 13 as they are delivered from the frame 44 and to slide them along a circular guide on the frame 3.
- 25 Referring specifically to Fig. 1, in which is disclosed a can filling machine embodying a corn measuring and feeding mechanism, similar in structure to that disclosed in Patent 473,885, a rotary corn receptacle 16 having a series of six or more openings in the bottom thereof, is secured to the vertical shaft 1 by means of a key 48. A stationary circular disk 17 having an opening 18 therein is adjustably secured to the sleeve 26 by means of a set screw 27. The sleeve 26 has screw threaded engagement with the hub 29 30 of the element 7 and is locked to this hub by means of a set screw 28. The cylinders 49 of which there is one for each opening in the bottom of the receptacle 16, form measuring chambers which are rotatable 35 with the receptacle 16 and element 14. The lower extremities of the cylinders 49 abut the can conveying element 14. The measuring chambers formed by the cylinders 49 communicate through passages 22 with the delivery chambers within which plungers 21 are vertically reciprocable. The plungers 21 are guided upon the wall of the receptacle 16 by means of guides 47, and are reciprocable to cut off the passages 22 and permit filling of the measuring chambers and to subsequently deliver the measured quantities of material to the cans 13, by means of the cam tracks 23 engaged by rollers 24 carried by the plungers 21. The cam tracks 23 are supported from the pads 8 of the frame elements 2. The pistons 19 are reciprocable within the cylinders 49 to alternately measure and deliver the material, by means of piston rods 20 reciprocable in openings 56 in the element 14. The piston rods 20 carry rollers 25 which are engageable with the cam track 15. The cam track 15 is disclosed as being formed directly in the can support 3, but this track may be formed on a separate piece attached to the can support 3. While the drawing discloses only two measuring and delivering devices, it will be understood that six or eight of these devices would ordinarily be employed. The other details of construction of the measuring and delivering mechanism not apparent from the present disclosure, will be readily understood by referring to the specification of Patent 473,885.
- 40 During the normal operation of the corn filling machine disclosed in Fig. 1, the vertical shafts 1, 38 are rotated in opposite directions as indicated by the arrows in Fig. 4, by means of power derived from the main shaft 6 through the gears 5, 4, 37, 39. The rotating shaft 1 carries with it the recessed conveying element 14 and receptacle 16, while the shaft 38 carries with it the can discharging disk 40. The cans 13 are fed upon the can supporting and guiding frame 3 and are transported along this frame by means of the element 14. The cans 13 are filled with corn during transportation along the frame 3, being eventually delivered to the disk 40 from which they are discharged. The corn is fed by gravity from the receptacle 16 through the opening 18 in the stationary plate 17, into the successive cylinders 49, while the corresponding pistons 19 and plungers 21 are in their lowermost positions, as indicated at the right of Fig. 1. As the filled measuring cylinders are advanced, communication with the receptacle 16 is automatically cut off and the pistons 20 and plungers 21 are operated by means of the cam tracks 15, 23 and rollers 24, 25 to force the measured batches of corn into the adjacent cans 13.
- 45 Referring specifically to Fig. 2, in which is disclosed a can filling machine embodying

a pea measuring and feeding mechanism, similar in structure to that disclosed in Patent 1,188,764, the hopper 51 and sealing cover 60 are vertically adjustably suspended 5 from the sleeve 59, the upper end of which has screw threaded engagement with the hub of the frame element 7 and has a hand wheel 32 secured thereto for the purpose of adjusting the sleeve 59 relatively to the frame element 7. The sealing cover 60 is fixed against rotation by means of a rod 63 secured to the plate 70. The pea measuring pockets 61 are rotatably suspended from the sleeve 59, being vertically adjustable by means of the 10 sleeve 59 and hand wheel 32. The element 62 is rotatable with the pockets 61, being secured to the shaft 1 by means of a key 65. The element 62 is provided with radial walls which drive the pockets 61, and forms a sliding joint with the upper plate of the element 64. The element 64 comprises spaced plates connected by a through passage communicating with the pockets 67 and sealed against communication with the interior of 15 the brine tank 69. The lower plate of the element 64 is provided with an opening 66 forming direct communication between the brine tank 69 and the successive pockets 67. The element 64 is fixed against rotation by means of an extension thereon engaging the rod 63. The series of pockets 67 are secured to the shaft 1 by means of a key 68 and have sliding engagement at their upper and lower extremities with the lower plate of the element 64 and with the plate 70 respectively. 20 The plate 70 forms a bottom for the brine tank 69 and also forms a means of support for this tank, being connected to the frame pads 8. The plate 70 has an opening 40 through one portion thereof adapted to deliver the measured quantities of peas and brine to the adjacent hoppers 50. The hoppers 50 are secured to a hub 71 which is fixed to the shaft 1 by means of a key 48. 45 The cam 15 and openings 56 which in the case of Fig. 1 served as actuators and guides respectively for the piston rods 20, serve no useful purpose in the pea filler and may be omitted, if it is not desired to convert the 50 filling machine into one of another type. Other details of construction and operation of this measuring and delivering mechanism, not apparent from the present disclosure, will be readily understood by referring 55 to the specification of Patent 1,188,764.

During the normal operation of the pea filling machine disclosed in Fig. 2, the shaft 1 is rotated as in the case of the corn filler, carrying with it the element 14, hoppers 50, 60 pockets 67 and pea measuring pockets 61. The peas are automatically fed from the hopper 51 into the pockets 61 from which they are discharged in measured quantities to the pockets 67. In the pockets 67 brine 65 is added to the peas, the batches of mixture

being eventually delivered to the hoppers 50 from which they are discharged into the adjacent cans 13. The element 14 serves to transport the cans 13 through the machine as hereinabove explained, and a disk 40 actuated as disclosed in Fig. 4, serves to discharge the filled cans 13. 70

Referring specifically to Figs. 3 and 4, in which is disclosed a filling machine embodying a so called "syrup" measuring and feeding mechanism, similar in some respects to the device disclosed in Patent 1,029,681, a rotary liquid receptacle 30 having a series of liquid feeding devices 35 associated with the bottom thereof, is rotatably suspended 80 from the sleeve 33 by means of a cap 34 secured to the hub 57. The hub 57 is secured to the shaft 1 by means of a key 48. The sleeve 33 has screw threaded coaction with the central hub of the frame element 7 and 85 has a hand wheel 32 secured thereto for the purpose of adjusting the sleeve 33 relatively to the element 7. The liquid feeding devices 35 are adapted to feed liquid from the receptacle 30 to the cans 13 and to automatically cut off the flow of liquid when the proper amount has been delivered to the can. The usual air vent pipes 31 are provided and coöperate with the feeding devices 35 to permit the escape of air. The cam tracks 90 95 36 engage rollers 53 associated with the feeding devices 35, and are secured to the pads 8 of the frame elements 2. The cam 15 and openings 56 which in the case of Fig. 1 served as actuators and guides respectively for the piston rods 20, serve no useful purpose in the liquid filler and may be omitted, if it is not desired to convert the filling machine into one of another type. Other details of construction and operation 100 105 of this measuring and feeding device not apparent from the present disclosure, will be readily understood by referring to the specification of Patent 1,029,681.

During the normal operation of the liquid filling machine disclosed in Figs. 3 and 4, the shaft 1 is rotated as in the case of the corn filler, carrying with it the element 14, receptacle 30 and feeding devices 35. The feeding devices 35 are automatically actuated 110 115 by means of the rollers 53 and cam tracks 36, to feed the proper amount of liquid from the receptacle 30 to the successive cans 13. The cans 13 are transported through the machine by means of the elements 14, and the disk 40 serves to deliver the filled cans 13 from the machine. 120

While the drawings disclose the invention as applied to only three different types of measuring and feeding devices, it is obvious 125 that other measuring and feeding devices, such as are ordinarily employed to measure and feed tomatoes, kraut, spaghetti, milk and other liquids, may also be designed to coöperate with one or more of applicant's 130

common elements. It will be noted that with the present invention, either the frame structure, the driving mechanism or the can transporting means may be furnished as an article of manufacture, these elements being coöperable with any of the measuring and feeding devices disclosed, regardless of the employment of any of the other common elements. The measuring and feeding devices are preferably made interchangeable so that a filler of one type may be readily converted into another type by merely replacing the measuring and feeding mechanism. The manufacturing cost is also enormously reduced due to the fact that a manufacturer of several types of fillers is with the use of the present invention, required to carry in stock only one style or type of frame structure, can transporting mechanism and driving mechanism.

It should be understood that it is not desired to be limited to the exact details of construction and operation herein shown and described, for various modifications within the scope of the appended claims may occur to a person skilled in the art.

It is claimed and desired to secure by Letters Patent:-

1. In a can filling machine, frame structure, can transporting structure associated with said frame structure, and drive structure associated with at least one of said structures, said structures being formed for interchangeable association with different types of can filling mechanisms.

2. In a can filling machine, frame structure, can transporting structure supported by said frame structure, and drive structure for operating said transporting structure, said structures being formed for interchangeable coöperation with different types of can filling mechanisms.

3. In a can filling machine, frame structure, can transporting structure supported

by said frame structure, and drive structure supported by said frame structure, said structures being formed for interchangeable coöperation with different types of can filling mechanisms.

4. In a can filling machine, frame structure, can transporting structure supported by said frame structure, and drive structure supported by said frame structure and coöperable with said transporting structure to drive the same, said structures being formed for interchangeable association with different types of can filling mechanisms.

5. In a can filling machine, frame structure, can transporting structure, and drive structure, said structures being formed for interchangeable coöperation with different types of can filling mechanisms, the first to support a mechanism, the second to transport cans in proper relation to be filled by said mechanism, and the third to drive said mechanism.

6. In a can filling machine, frame structure, can transporting structure supported by said frame structure, and drive structure for said transporting structure, said structures being formed for interchangeable simultaneous coöperation with different types of can filling mechanisms, the first to support a mechanism, the second to transport cans in proper relation to be filled by said mechanism, and the third to drive said mechanism.

7. In a can filling machine, frame structure, can transporting structure supported by a vertical medial portion of said frame structure, and drive structure supported by a horizontally medial portion of said frame structure, said structures being formed for interchangeable coöperation with different types of can filling mechanisms.

In testimony whereof the signature of the inventor is affixed hereto.

OSWALD H. HANSEN.
